U.S. patent application Ser. No. 29/311,362, filed herewith and entitled “Foot for a Side Mirror for a Vehicle”.

FIG. 1 is a rear perspective view of a first embodiment of a side mirror for a vehicle according to our novel design;

FIG. 2 is a side perspective view thereof;

FIG. 3 is a rear view thereof;

FIG. 4 is a front view thereof;

FIG. 5 is a side view thereof; and

FIG. 6 is a top view thereof.

FIG. 7 is a side perspective view of a second embodiment of the side mirror for a vehicle according to our novel design;

FIG. 8 is a side perspective view thereof;

FIG. 9 is a rear view thereof;

FIG. 10 is a front view thereof; and

FIG. 11 is a top view thereof.

FIG. 12 is a rear perspective view of a third embodiment of the side mirror for a vehicle according to our novel design;

FIG. 13 is a side perspective view thereof;

FIG. 14 is a rear view thereof;

FIG. 15 is a front view thereof;

FIG. 16 is a side view thereof; and

FIG. 17 is a top view thereof.

FIG. 18 is a side perspective view of a fourth embodiment of the side mirror for a vehicle according to our novel design;

FIG. 19 is a side perspective view thereof;

FIG. 20 is a rear view thereof;

FIG. 21 is a front view thereof; and,

FIG. 22 is a top view thereof.

The third embodiment is a mirror image of the side mirror for a vehicle as shown in FIGS. 1-6. The fourth embodiment is a mirror image of the side mirror for a vehicle as shown in FIGS. 7-11.

In the drawings, the broken lines show portions of a side mirror for a vehicle and form no part of the claimed design.
